UNITED STATES PATENT OFFICE.

GEORGE F. BROWN, OF BROOKLYN, NEW YORK.

DESIGN FOR A WEDDING-CARD.

SPECIFICATION forming part of Design No. 19,224, dated July 23, 1889.

Application filed May 11, 1889. Serial No. 310,470. Term of patent 7 years.

To all whom it may concern:

Be it known that I, GEORGE F. BROWN, a citizen of the United States, residing at Brooklyn, in the county of Kings and State of New York, have invented and produced a new and original Design for Stationery, and especially for Wedding-Cards, Wedding-Invitations, and the Like, of which the following is a specification, reference being had to the accompanying drawings, forming a part thereof.

Figure 1 is a perspective view of a card containing my design. Fig. 2 is a perspective view of another card containing the same design, in which the edges have a different detail in ornamentation.

The characteristic or leading feature of my design consists of the wedding-card having upon its surface a panel or panels with a group or groups of bells thereon.

My said design is preferably arranged as shown in the drawings, in which C represents a sheet of wedding-card, invitation, or note paper, and A A' panels thereon, and B B groups of bells upon said panels.

I claim—

The design for a wedding-card, as herein described and shown.

GEORGE F. BROWN.
